PLAYGROUND CLIMBER REPRESENTING A CATERPILLAR

Robert S. Wormser, Hillsdale, Mich., assignor to Game Time, Inc., Litchfield, Mich.

Filed Feb. 23, 1973, Ser. No. 335,068

Term of patent 14 years

Int. Cl. D21—02

U.S. Cl. D34—5 H

FIG. 1

FIG. 2

FIG. 1 is a perspective view of a playground climber representing a caterpillar as taken from the front and right side thereof in accord with my new design,

FIG. 2 is a top, plan view,

FIG. 3 is a front, elevational view of a climber in accord with my new design, and

FIG. 4 is a rear, elevational view.

I claim:

The ornamental design for a playground climber representing a caterpillar, substantially as shown and described.
